UNITED STATES PATENT OFFICE.

AUGUST BORLEIS, OF RASPEBURG, BALTIMORE, MARYLAND.

SCISSORS SHARPENER.

Application filed June 13, 1922. Serial No. 567,919.

To all whom it may concern:

Be it known that I, AUGUST BORLEIS, a citizen of the United States, residing at Raspeburg, in the city of Baltimore and State of Maryland, have invented certain new and useful Improvements in Scissors Sharpeners; and I do hereby declare the following to be a full, clear, and exact description of the invention, such as will enable others skilled in the art to which it appertains to make and use the same.

My invention relates to scissors sharpeners.

Among the objects of my invention are:

15 To provide a scissors sharpener capable of producing a fine cutting edge without the use of abrasive materials.

20 To produce a scissors sharpener which shall automatically guide the sharpening portion thereof with reference to the scissors blades during the sharpening operation.

To produce a scissors sharpener which can be operated by unskilled persons.

25 To produce a scissors sharpener that shall be small, simple, cheap and of such nature that it comports with the other contents of a lady's work basket.

These and other objects of my invention 30 will become apparent in the following specification, reference being had to the accompanying drawings, and the means by which said objects are effectuated will be definitely pointed out in the claims.

35 In the drawings:

Figure 1 is a side view of a pair of scissors showing my improved sharpener in one of the positions it assumes during the sharpening operation.

40 Fig. 2 is an enlarged section along the line 2—2 in Fig. 1 looking in the direction of the arrow.

Fig. 3 is an enlarged view of my improved sharpener when viewed in the direction of the arrow 3 in Fig. 2, the scissors blades being omitted.

50 5 is the body of my improved sharpener. Said body is provided with a face 6 against which the flat inner surface of the scissors blade 7 bears during the sharpening operation. Said body is also provided with a point 8 against which the outer surface of the scissors blade 9 rests during the sharpening operation.

55 The sharpening offset 10 is provided with faces 11 and 12 that are preferably flat, ap-

proximately parallel and disposed at approximately the same angle to the surface 6 as the angle included between the flat inner surfaces of the blades 7 and 9 and their cutting surfaces. Adjacent the surfaces 11 and 12, clearance grooves 13 and 14 are provided for a purpose hereinafter explained.

The portions of the sides 15 and 16 of the sharpener to the left of the dotted line 17 are substantially flat, the portion of the side 15 to the right of said line is convex in shape and the portion of the side 16 to the right of said line is concave in shape, said concavity being provided for the reception of the thumb of the left hand of the operator.

In the drawings I have shown the general contour of my improved sharpener to be circular and cut away to form the surface 6 and point 8, but it is to be understood that the general contour may be of any desired shape, provided the parts heretofore described be shaped and located as set forth. I have also shown a hole therein which is 80 for the purpose of mounting the sharpener upon a string.

In Fig. 2 I have shown the offset 10 as sloping downwardly toward the right, but it is to be understood that it is to be so shaped when designed for use with ordinary scissors and snips. If it is to be used with left hand snips, the angularity of the offset would either be reversed or when applied to the left hand snips the concave side would 90 be placed away from the handle thereof instead of toward the handle as in Fig. 1.

My improved sharpener is preferably made of hardened steel.

The manner of use of my improved sharpener is as follows:

The operator grasps the sharpener between the thumb and first two fingers of his left hand with the face 16 towards him. He then widely opens the blades 6 and 7 and places the offset 10 as close to the screw joining the blades as possible. He then presses the handles of the scissors together and at the same time moves the sharpener towards the points of the blades. This motion penes the cutting edge of the scissors and makes a sharp shearing edge thereupon.

Thus it will be seen that I provide a simple, cheap and efficient scissors sharpener capable of use by unskilled persons.

While I have shown one embodiment of my invention, it is to be understood that

this is for purposes of illustration only, for changes may be made therein without departing from the spirit of my invention.

I claim:—

- 5 1. In a scissors sharpener, the combination of a body having a concave side, a sharpening device on said body and means on said body for guiding scissors blades with reference to said device during the
- 10 sharpening operation, said side being so located with reference to said device that when the thumb of the left hand is applied

to said side, said device will be in the proper location for the application of said blades to said device.

2. In a scissors sharpener, a body having a face for guiding the inside surface of one scissors blade, a point for guiding the outside surface of the other scissors blade, and an offset having faces for sharpening said 20 blades.

In testimony whereof, I affix my signature.

AUGUST BORLEIS.
